Fig. 4

Fig. 5

Fig. 6

FIG. 1 is a front perspective view of a dental instrument tray embodying our new design; the broken line illustrating the dental unit and related handpieces are disclosed for illustrative purposes only;

FIG. 2 is an enlarged perspective view of the dental instrument tray;

FIG. 3 is a top plan view of the dental instrument tray of FIG. 2;

FIG. 4 is a front elevation of the dental instrument tray of FIG. 2;

FIG. 5 is a right end elevation of the dental instrument tray of FIG. 2; and

FIG. 6 is a cross sectional view, taken on line 6-6 of FIG. 4.

We claim:

The ornamental design for a dental instrument tray, substantially as shown and described.
